UNITED STATES PATENT OFFICE.

ALFRED A. RUTTAN AND CHARLES E. HUTCHINGS, OF ROCHESTER, NEW YORK,
ASSIGNORS TO EASTMAN KODAK COMPANY, OF ROCHESTER, NEW YORK, A
CORPORATION OF NEW YORK.

VIEW-FINDER.

1,066,848.

Specification of Letters Patent.

Patented July 8, 1913.

Application filed January 16, 1913. Serial No. 742,383.

To all whom it may concern:

Be it known that we, ALFRED A. RUTTAN and CHARLES E. HUTCHINGS, both of Rochester, in the county of Monroe and State of New York, have invented certain new and useful Improvements in View-Finders; and we do hereby declare the following to be a full, clear, and exact description of the same, reference being had to the accompanying 10 drawings, forming a part of this specification, and to the reference-numerals marked thereon.

Our present invention relates to view finders and more particularly to collapsible 15 finders, and it has for its object to provide a simple and efficient device of this character.

A further object of the invention is to produce a finder that will fold automatically 20 upon contact with a rigid part against which it is disposed and which will also automatically expand to an accurate operative position.

To these and other ends the invention consists in certain improvements and combinations of parts all as will be hereinafter more fully described, the novel features being pointed out in the claims at the end of the specification.

30 In the drawings: Figure 1 is a side elevation of a finder in operative position constructed in accordance with and illustrating one embodiment of our invention. Fig. 2 is a top plan view; Fig. 3 is a vertical section taken substantially on the line 3^a—3^a of Fig. 2; Fig. 4 is a similar section with the parts in folded position; Fig. 5 is a front elevation, and Fig. 6 is a bottom plan view of the top lens support.

40 Similar reference numerals throughout the several figures indicate the same parts.

The device illustrated is a finder designed particularly for use in photographic cameras, such as folding cameras, and the exact 45 part thereof upon which it is mounted is immaterial for the present purposes, as it will be understood that there are many parts of a folding camera upon which the finder may be mounted in a position in 50 which it is desirable or necessary that it collapse or extend itself accordingly as the camera is folded or extended.

Referring more particularly to the draw-

ings in this view, 1 indicates a plate supporting the front or field lens 2. In the present instance, the mechanism for directly mounting the lens also serves as a pivot about which the finder as a whole may be rotated between either of two positions 90° apart to provide, as usual, for the use of the camera with either of two adjacent edges of the sensitized plate on the horizontal. To these ends, the front support 1, mentioned, is provided with a forwardly projecting collar 3 that passes through a circular aperture in a main support or plate 4 so as to turn therein as a bearing. The lens tube 5 by which the lens 2 is directly carried, threads into the collar 3 and has a shoulder 6 bearing on the outside of the plate 4, 70 whereby the front lens support 1, and, indeed, the whole finder structure, is held assembled on the main support. A pin 7 projecting rearwardly from the main support 4, may coöperate with a segmental slot 8 75 on the front lens support 1 to limit the swinging movements of the finder and define its two operative positions.

The support for the top or reflecting lens 9 embodies, in the present instance, a flanged 80 and apertured frame 10 in which the said lens is retained by friction or the spring tension of the flanges of the frame, the lens being preferably provided with a metal binding 11. The rear end of this frame is 85 hinged or pivoted at 12 to the upper portion of a plate 13 that is provided with an angle mirror 14 in the form, as preferred, of a highly polished metal surface, while the lower end of the angle mirror plate 13 is 90 hinged or pivoted at 14^a to the lower portion of the front lens support 1.

The support 1 is preferably provided with rearwardly turned side flanges 15 in which are formed longitudinal guiding slots 16, 95 and the projecting ends 17 of a preferably continuous bar 18 that passes transversely through the frame 10, constitute portions on the top lens support coöoperating with said guides 16. A spring 19 encircling the pivot 14^a, normally holds the finder expanded in an operative position by its tendency to throw the angle mirror 13 rearwardly where it is halted at the proper angle by reason of its connection to the top mirror support, 100 and similarly, the latter is held in its proper

horizontal position by the pressure thus exerted which carries its projection 17 to the extreme upper ends of the guides or slots 16. In this connection, the upper portions 5 of both of the said slots are preferably provided with rearwardly inclined cam portions 20 which insure the movement of the said projection to the extreme limit of the slot and avoid the said projection reaching 10 a dead center with respect to the exertions of the spring 19. When force is exerted in a forward direction at the rear of the angle mirror 13 by contact thereof with a fixed body, or otherwise, the mirror moves 15 forwardly to the folded position of Fig. 4, substantially parallel to the front lens support 1. While this is being accomplished, the projections 17 on the top mirror support 10 slide downwardly in the slots 16, 20 again avoiding the dead center by reason of the cam portions 20, and the top mirror support assumes a folded position in rear of the front lens support 1 and between the latter and the mirror 13, as also shown in Fig. 4. 25 Of course, when the forward pressure against the mirror is released, the finder again automatically assumes an operative position, its normal tendency being to expand. 30 A spring washer 21 may be interposed between the front lens support 1 and the main support 4 to frictionally retard the turning movement of the finder as a whole and to retain it in either of the two positions to 35 which it may be adjusted.

We claim as our invention:

1. In a folding view finder, the combination with a front lens support, of a top lens support and an angle mirror adapted to be 40 folded to positions in rear of the support substantially in parallelism to each other and to the support.
2. In a folding view finder, the combination with a front lens support, and an angle 45 mirror pivoted thereto and adapted to fold to a position substantially parallel therewith, of a top lens support pivoted to one of

said parts and adapted to assume a folded position between them.

3. In a folding view finder, the combination with a front lens support, and an angle mirror pivoted thereto and adapted to fold to a position substantially parallel therewith, of a top lens support pivoted to one of said parts at one end, and a continuous guide 55 on the other part in which the other end of the top lens support is arranged to travel whereby the latter is caused to assume a folded position between the other parts as the angle mirror is moved toward the front 60 lens support.

4. In a folding view finder, the combination with a front lens support having a rearwardly turned flange at one side thereof provided with a slot constituting a guide and 65 an angle mirror pivoted at its lower end to said front lens support, of a top lens support pivoted at its rear end to the upper end of the angle mirror and having a portion at its front end coöperating with the slot or 70 guide, on the front lens support whereby the top lens support is caused to assume a folded position between the other parts as the angle mirror is moved toward the front lens support. 75

5. In a folding view finder, the combination with a front lens support provided with a longitudinal guide having a cam portion, and an angle mirror pivoted thereto and adapted to fold to a position substantially 80 parallel therewith, of a top lens support pivoted to the angle mirror at its rearward portion and having a member at its front portion coöperating with the guide on the front lens support whereby the top lens support is caused to assume a folded position between the other parts as the angle mirror is moved forwardly. 85
